(57) **CLAIM**

The ornamental design for a tyre, as shown and described.

DESCRIPTION

FIG. 1 is a front, right side perspective view of a tyre showing our new design;

FIG. 2 is a front elevation view thereof;

FIG. 3 is a partial front elevation view, taken between lines 3—3 in FIG. 2, shown at an enlarged scale; and,

FIG. 4 is a side view thereof.

The broken lines depict environmental subject matter only and form no part of the claimed design.
